Primary Examiner — Barbara Fox*Assistant Examiner* — Kimberly Barnes(74) Attorney, Agent, or Firm — Miller, Matthias & Hull LLP(57) CLAIM

The ornamental design for a portion of a display screen with icon group, as shown and described.

DESCRIPTION

The FIGURE is a front view of a portion of a display screen with icon group showing the new design.

The broken lines shown in the drawing illustrate portions of the display screen with icon group that form no part of the claimed design.
